WILLIAM H. BAKER, OF MONTREAL, QUEBEC, CANADA, ASSIGNOR TO DRAPER CORPORATION, OF HOPEDALE, MASSACHUSETTS, A CORPORATION OF MAINE.

COP-HOLDING SKEWER FOR LOOMS.

1,416,157.

Specification of Letters Patent. Patented May 16, 1922.

Application filed April 2, 1919. Serial No. 287,093.

To all whom it may concern:

Be it known that I, WILLIAM H. BAKER, a citizen of the United States, and resident of the city of Montreal, in the Province of Quebec and Dominion of Canada, have invented certain new and useful Improvements in Cop-Holding Skewers for Looms, of which the following is a full, clear, and exact description.

10 This invention relates to improvements in cop holding skewers for looms, and the object of the invention is to provide a skewer which will hold a cop securely in place and prevent breaking of the cop.

15 A further object is to provide a skewer, the spike of which may be very easily inserted into a cop.

20 A still further object is to provide a skewer of strong, durable and inexpensive construction, particularly adapted to withstand the battering incident to use in automatic weft replenishing looms.

25 Great difficulty has been experienced in maintaining cops in proper position on the skewers which support them in the shuttles. At every second pick of the loom, the inertia of the cop tends to slide it off the skewer when the shuttle comes to rest and at alternate picks the inertia of the cop tends to

30 slide it off the skewer when the shuttle commences to move. Sometimes the whole cop moves and jams up against the thread outlet of the shuttle, resulting in a breakage of the thread. At other times, the butt end

35 of the cop will remain firmly in position while the tip end will move, thus resulting in what is known as a broken cop. This condition has prevailed for many years and numerous attempts have been made to

40 devise a skewer which will hold the cop against this movement which is fatal to the successful operation of a loom. The most successful and most generally used of these skewers are formed with their spikes in the

45 form of elliptic springs, which are compressed or flattened when cops are forced on and which exert an outward or expansive pressure on the cops tending to hold them against movement. Following the na-

50 ture of an elliptic spring, such a spike exerts the maximum holding effect at a point midway between the ends of a cop and practically no holding effect toward the tip end of the cop, with the result that while the greater portion of a cop is securely held,

the tip end frequently breaks away from the remainder, so that the cop is ruined. An attempt has been made to overcome this by making the halves of the spike of wavy or corrugated form. These spring spikes have 60 the great disadvantage that they resist insertion in a cop and considerable skill and strength are necessary to properly place a cop on such a skewer.

According to the present invention, the 65 skewer spike is made in two longitudinally separate parts having relative movement in the axial direction of the skewer and provided on their adjacent surfaces with cams which tend to separate the parts during 70 relative movement in one direction, so that the diameter of the spike is increased. This relative movement of the parts is produced by the inertia of one of the parts, assisted by a spring arranged in the head of the 75 skewer which normally maintains a certain expansive pressure on a cop. The head of the skewer is constructed of such materials and in such a way that it is exceedingly strong and durable and furthermore forms 80 a receptacle for the spring, so that valuable cop space on the skewer is not taken up by the spring.

In the drawings which illustrate the invention:—

Fig. 1 is a side elevation of the device.

Fig. 2 is a plan view.

Fig. 3 is a longitudinal section through the centre of the head.

Fig. 4 is a cross section on the line 4-4, 90 Figure 1.

Fig. 5 is a longitudinal section of the tip end of the spike.

Fig. 6 is a view similar to Figure 3, illustrating a modification.

Fig. 7 is a fragmentary view of the butt end of the spike partly in section illustrating a further modification.

Referring more particularly to the drawings, 11 designates the head and 12 the spike 100 of a cop skewer. The head is in the form of a metal cup 13 having a hollow neck 14 projecting outwardly from the bottom thereof. The exterior of the cup is provided with circumferential ribs 15 adapted to engage 105 in the jaws of a shuttle to hold the skewer against longitudinal movement. An annulus 16 of fibre or other suitable material surrounds the neck and covers the outer surface of the cup bottom. This annulus is held 110

in place by a metal washer 17 of larger diameter than the neck, which is bedded into the washer so as to be flush with or slightly below the surface thereof. The end of the 5 spike is reduced in diameter to form a shoulder 18, which bears against the inner surface of the cup bottom, the reduced portion 19 passing through the neck and being riveted over the washer 17. The spike 12 comprises a portion 20 fixed with respect to the 10 head and a portion 21 movable in the axial direction of the skewer with respect to the portion 20 and the head. The cross section of these portions is approximately semi-circular in the greater portion of their lengths, 15 as clearly shown in Figure 4, and they are arranged with their flat surfaces adjacent. The cross sectional area of the part 20 is slightly greater than the cross sectional area 20 of the part 21, so that the part 20 will be stiffer than the part 21. The tip end 22 of the part 20 extends beyond the end 23 of the part 21 and both taper in width but not in thickness, so that they come ultimately to 25 approximately circular cross sections, the tip 23 being very much smaller than the tip 22 and fitting slidably in the bore 24 of the tip 22. The butt end of the part 21 stops short of the part 20 and is suitably enlarged 30 adjacent its end forming projections 25 against which one end of a helical spring 26 may press. This spring surrounds both parts 20 and 21 and its opposite end is seated in the bottom of the cup 13. It will thus 35 be seen that the effect of the spring in expanding is to urge the part 21 in the axial direction of the skewer toward the tip thereof. The adjacent faces of the parts 20 and 21 are provided with co-engaging cams 27 so 40 disposed as to force the part 21 away from the part 20 during movement of the part 21 toward the tip of the skewer. These cams may be in any suitable number and position so as to give a practically uniform support 45 to the part 21.

In the form shown in Figure 6, a cup-shaped washer 28 having an outwardly turned flange 29 at its open end is slidably mounted on the fixed part 20 of the skewer spike. The spring 26 is arranged between the bottom of the cup 13 and the flange of the washer and operates to urge the washer out of the cup 13. The part 21 of the skewer spike is provided with an outwardly turned foot 30 located within the washer 28 and adapted to press against the bottom thereof, so that the part 21 will be urged with the washer toward the point of the skewer.

In Figure 7, the foot 30^a of the part 21, 460 instead of being turned away from the part 20, is turned toward the part 20 and provided with an aperture 31 through which the part 20 passes. Spring pressure may be applied to the part 21 in the manner shown in 485 Figure 3 or in the manner shown in Figure

6, or in any other suitable manner, the foot 30^a forming an abutment for the spring corresponding to the projections 25 or an abutment for the washer corresponding to the foot 30. 70

The operation of the device is extremely simple and is entirely automatic in its action. When a cop is to be applied to the skewer the operator grasps the skewer by its head with one hand and the cop in the other hand in the usual manner and passes the spike through the cop from butt to tip. In this movement, the spike part 21 engages frictionally with the core of the cop and is pressed toward the part 20 and also drawn back 75 relatively to the part 20 against the action of the spring 26, so that the cams of the part 21 slide down on the cams of the part 20 and enable the part 21 to approach the part 20, so that the spike contracts and 80 may be very easily pressed into the cop. As soon as the pressure is relieved, the spring 26 becomes effective and urges the part 21 toward the point of the spike. In such a movement, the cams of the two parts move 85 over one another and force the parts 20 and 21 apart, so that the spike tends to expand within the cop and grip the same very tightly. When the skewer is placed in a shuttle and the latter set in motion, the 90 skewer is moved longitudinally. When the skewer starts to advance (move point first) the movement is applied through the head and spike part 20 which is rigid therewith. The inertia of the part 21 and the cop produces a tendency for these two to set back 95 toward the head of the skewer. During the movement, the spring 26 loosens the grip of the spike in the cop, as previously described. When the advance of the shuttle is checked, 100 the inertia of the cop and part 21 tends to keep them in movement after the part 20 has stopped. Any such movement of the part 21 is accompanied by an expansion of the spike, so that the grip of the spike on the 105 cop is increased and the cop securely held against sliding toward the point of the skewer. When the skewer commences its return movement (head first), the movement of the shuttle is communicated as before 110 through the head and spike part 20 and the inertia of the cop and part 21 tend to cause them to slip toward the skewer point. Such movement would produce the same results 115 as are produced by the stoppage of movement just described. When the shuttle reaches its starting point and movement is again checked, the inertia of the cop and part 21 tend to slide them toward the head 120 of the skewer. Any movement of the part 21 toward the head of the skewer is accompanied by a loosening of the grip on the cop, so that the cop will be free to move toward the skewer head. It will thus be seen that 125 at one side of the loom, there will be a series 130

of distinct impulses tending to loosen the grip of the skewer in the cop and urging the cop toward the skewer head, while at the opposite side of the loom there will be an equal 5 number of equally strong impulses urging the skewer to expand within the cop and hold same against movement away from the skewer head. The cup-shaped head provides a receptacle for the spring and is obviously 10 much stronger than the wooden heads usually applied to skewers. The fibre ring on the end of the head is much stronger than wood and has about the same resiliency. The construction of the head with 15 the ribs 15 forming an integral part thereof is much superior to the ordinary construction and is especially efficient for use in automatic looms where the skewers are subject to very rough usage. The spike receiving 20 portions of the head being entirely of metal, it is obvious that the spike may be attached much more securely than is possible in the ordinary wooden-headed skewer. The use of a metal head enables the formation 25 of a large deep cup for the reception of the spring 26 or the butt end of the cop if an ordinary spike is attached to the head, thus enabling a longer cop to be used than is possible with a wooden-headed skewer of the 30 same length as the metal-headed skewer.

While the spike has been shown and described as attached to a head suitable for use in an automatic loom, it will be understood that the invention is not limited to such 35 a combination, as the spike may be pivoted at one end in a shuttle in the well known manner. In such an arrangement the spring actuating the part 21 will be arranged between the part 21 and any suitable form 40 of abutment on the part 20.

In placing a cop on the spike, the operation may be greatly facilitated by manually relieving the part 21 of the load of the spring by pressing directly on the spring. 45 In the form shown in Figure 6, the washer will serve as a means to compress the spring and greatly facilitate the operation.

Having thus described my invention, what I claim is:—

- 50 1. A cop spike divided along its longitudinal axis into two parts relatively movable in their longitudinal direction, and a spring urging said spike parts to movement in opposite directions.
- 55 2. A device according to claim 1, in which one of the parts projects at both ends beyond the other part, and operative connection between said parts at both ends.
- 60 3. A device according to claim 1, in which the parts are of unequal length.
- 65 4. In combination with a device according to claim 1, abutments carried by the butt ends of the spike parts, between which the spring is located.

65 5. A device according to claim 1, in which

the tip end of one part is tubular and receives the tip end of the other part.

6. A device according to claim 1, in which one of the parts has greater flexibility than the other. 70

7. In combination with a device according to claim 1, a cam on one of said parts and a cam on the other of said parts engaging with said first cam, said cams being operative upon relative longitudinal movement 75 of the parts in one direction to simultaneously move the parts away from one another.

8. A device according to claim 1, in which the spike parts are each of substantially semi-circular cross section throughout the 80 greater part of their length and are of substantially cylindrical formation at their tip ends, the tip end of one part having an opening to receive the tip end of the other part.

9. A cop spike divided along its longitudinal axis into two parts relatively movable in their longitudinal direction, said parts being of unequal flexibility and length and the tip end of the longer part being adapted to slidably receive the tip end of the shorter 90 part, abutments carried by the butt ends of said parts, and a spring mounted in compression between said abutments.

10. In combination with a device according to claim 1, co-engaging cams carried by 95 the spike parts and arranged to regulate the distance between the parts proportionately to their relative longitudinal movement.

11. A cop spike for a loom shuttle comprising two parts, one adapted to be rigidly held by the shuttle, and the other of which is operatively connected with such rigidly held part so as to move longitudinally with respect thereto, and a spring acting upon the longitudinal moving part and tending to 105 move it toward the tip of the skewer.

12. In combination with a device according to claim 11, cams on said parts arranged to separate the parts upon predetermined relative movement of the parts. 110

13. A device of the class described comprising a spike longitudinally divided into two relatively movable parts, a head rigidly attached to the butt end of one of said parts, abutments on the butt end of the other of said parts, and a spring connected between said head and abutments arranged to urge the parts to relative longitudinal movement. 115

14. A device according to claim 13, in which the head is cup-shaped for the reception of the spring. 120

15. A device according to claim 13, in which the tip end of one of said parts is provided with an opening to receive the tip end of the other part and to limit the relative longitudinal movement of the parts. 125

16. In combination with a device according to claim 13, in which the head carrying part is less flexible, co-engaging cams carried by said spike parts adapted to separate 130

the parts upon movement of said movable part in one direction.

17. In a cop skewer, a spike, a cup having an opening in the bottom thereof through which said spike passes, an external neck surrounding the opening, an annulus of cushioning material surrounding the neck, a washer over which the spike is riveted retaining said annulus, and external circumferential ribs on said cup adapted for cooperation with a shuttle.

18. A device according to claim 17, in

which the cup neck and circumferential ribs are formed of a single piece of metal and the annulus formed of fibre.

15

19. In a cop skewer, a cup having an opening in the bottom thereof, an annulus of cushioning material outside the bottom of said cup, and a spike passing through the cup bottom and annulus and securing the cup and annulus together.

In witness whereof, I have hereunto set my hand.

WILLIAM H. BAKER.
